(57) **CLAIM**

(21) Appl. No.: **29/299,885**

The ornamental design for a ready to process fluid transfer cart, as shown and described.

(22) Filed: **Jan. 7, 2008**

DESCRIPTION

(51) **LOC (9) Cl.** **24-01**

FIG. 1 is a perspective view of the ready to process fluid transfer cart showing our new design.

(52) **U.S. Cl.** **D24/185**; D34/17

FIG. 2 is a front view of the ready to process fluid transfer cart of FIG. 1.

(58) **Field of Classification Search** D24/107, D24/177, 185–186; D6/465, 476, 478–479; D34/12–27; 108/209, 177, 189; 280/47.34–47.35, 280/79.11, 79.2–79.3

FIG. 3 is a back view of the ready to process fluid transfer cart of FIG. 1.

See application file for complete search history.

FIG. 4 is a left side view of the ready to process fluid transfer cart of FIG. 1.

(56) **References Cited**

FIG. 5 is a right side view of the ready to process fluid transfer cart of FIG. 1.

U.S. PATENT DOCUMENTS

FIG. 6 is a top plan view of the ready to process fluid transfer cart of FIG. 1; and,

FIG. 7 is a bottom plan view of the ready to process fluid transfer cart of FIG. 1.
